(57) **CLAIM**

The ornamental design for a pleated face mask, as shown and described.

DESCRIPTION

FIG. 1 shows a perspective view of a pleated face mask showing our new design.

FIG. 2 shows a top view of the face mask according to FIG. 1.

FIG. 3 shows a front view of the face mask according to FIG. 1.

FIG. 4 shows a left side view of the face mask according to FIG. 1.

FIG. 5 shows a back view of the face mask according to FIG. 1.

FIG. 6 shows a right side view of the face mask according to FIG. 1.

FIG. 7 shows a bottom perspective view of the inhaler according to FIG. 1; and,

FIG. 8 shows a perspective view of the face mask being worn by a person according to FIG. 1.

The broken line showing is for illustrative purposes only and forms no part of the claimed design.
